UNITED STATES PATENT OFFICE.

CHARLES F. MOCK, OF LOUISVILLE, KENTUCKY.

HAME.

SPECIFICATION forming part of Letters Patent No. 531,824, dated December 25, 1894.

Application filed June 6, 1894. Serial No. 513,601. (No model.)

To all whom it may concern:

Be it known that I, CHARLES F. MOCK, a citizen of the United States, residing at Louisville, in the county of Jefferson and State of Kentucky, have invented certain new and useful Improvements in Sheet-Metal Hames; and I do hereby declare the following to be a full, clear, and exact description of the invention, such as will enable others skilled in the art to which it appertains to make and use the same.

The object of my invention is to provide a cheap, light and strong hame and it consists in constructing a hame of sheet metal folded lengthwise, so as to form a U shaped channel, bent into proper shape and provided with the necessary strap holes, rings and hook.

I am aware that hames have been made of sheet metal before and my hame is an improvement on those heretofore made in strength, convenience and simplicity of construction.

In the drawings, Figure 1 is a side elevation of my hame. Fig. 2 is a top plan view showing my mode of attaching the rings for breast chain and reins and the loop for the hame string. Fig. 3 is a plan view of the strip of sheet metal from which the hame is made showing the projection through which the holes are pierced for the hame straps and Fig. 4 is a transverse section of my hame.

Similar letters indicate similar parts throughout the several drawings.

B represents the hame.

A represents the metal strip forming the body of the hame; A', an integral projection on one side of A, adapted to be pierced with strap holes a, a, a', the loop for the hame string provided with a shank a².

a³ a⁴ are the rivets by which the shank a² is attached to the body of the hame.

b is the rein ring; b', the breast strap ring; b², the tug hook; c, the eyed rivet by which the rein ring is attached to the hame and c' the similar rivet by which the breast chain ring and tug hook are attached to the hame.

In constructing my hame I take a strip of sheet metal as shown in Fig. 3 having an offset or projection on one side as shown at A', at a suitable distance from the end designed

for the top of the hame, adapted to be pierced with holes a, a, for the hame straps. All the angles of this strip are preferably slightly rounded. The metal strip A is then folded or doubled lengthwise forming a U shaped channel as indicated in Fig. 4, and bent into the proper hame shape shown in Fig. 1. The shank a² of the loop a' for the hame string, is riveted into the lower end of the channel by rivets a³ passing through both folds of the metal. The rein ring b is attached to the hame by the eyed rivet c and the breast strap ring b' by the eyed rivet c'. The tug hook b² is held in place in the channel between the two sides of the hame by the rivet c', also, which passes through a hole, in the stem of the hook near its bottom, sufficiently large to allow the hook some vertical play.

The folding of the metal, forming a channeled frame as described, strengthens the hame and the mode of attaching the rings, hook and hame string loop a' is simple and convenient and tends to strengthen the hame and keep it in shape.

The construction of parts is such that they are easily replaced if broken or needing repair.

It will be observed that the blank A is flat and gradually diminishes in width from an intermediate point toward its ends, the edges converging on similar slanting lines. The sheet is folded longitudinally between its edges and curved outward between its ends to attain the required form to adapt it to the collar, as most clearly shown in Fig. 1, the open side extending outward. By this construction the inner edge of the hame is rounded and does not bear injuriously on the collar and the inner side, being broad, obtains an extended bearing upon the outer face of the collar.

Having thus described my invention, what I claim as new, and desire to secure by Letters Patent, is—

As a new article of manufacture a hame formed from a flat sheet metal blank, whose opposite edges taper similarly from a point between toward its ends, and having an integral projection at one side near the top end, pierced to provide a series of openings to re-

ceive the hamestrap, said blank being folded longitudinally between its edges and curved outward between its ends to adapt it to the collar, the outer edge of the hame being open, 5 a string loop having a flattened end fitted and secured between the walls of the lower end of the hame, eye rivets c c' connecting the folds of the blank, rings b b' fitted in the apertured ends of the said eye rivets, and a tug hook se-

cured between the said folds by the eye rivet ro c' , substantially as specified.

In testimony whereof I affix my signature in presence of two witnesses.

CHARLES F. MOCK.
